UNITED STATES PATENT OFFICE.

WALTER M. FISCHBACH, OF MILWAUKEE, WISCONSIN.

GUARD-RAIL STRUCTURE FOR TOY RAILWAY TRACKS.

Application filed August 18, 1924. Serial No. 732,973.

To all whom it may concern:

Be it known that I, WALTER M. FISCHBACH, a citizen of the United States, residing at Milwaukee, in the county of Milwaukee and State of Wisconsin, have invented certain new and useful Improvements in Guard-Rail Structures for Toy Railway Tracks, of which the following is a specification.

10 This invention relates to improvements in tracks for toy electric railways and more particularly to a guard for such tracks.

It not infrequently happens that in the operation of a toy electric railway, the locomotive and the train of cars drawn thereby will overturn when traveling at high speed around the curves in the track. no means, so far as I am aware, having been previously employed or provided to 20 overcome this disadvantage. It is, therefore, the primary object of the present invention to provide a novel guard rail for tracks of this class and a novel means for supporting the rail in such position with 25 relation to the track sections in connection with which it is employed, as to constitute a guide along which the locomotive of the railway may run in rounding a curve, thereby positively insuring against any overturning 30 of the locomotive.

Another object of the present invention is to provide a guard rail and supporting means therefor which may be employed in connection with any of the standard tracks 35 now upon the market and readily adapted to sections of such track without the employment of any tools whatsoever and so adjusted as to properly sustain the locomotive of the railway in an upright position as it 40 rounds curves in the track.

The locomotives of toy railways are made in various sizes and, moreover, locomotives of different heights, widths and lengths may be run upon the same gauge of track. 45 Therefore, the present invention has as another object of importance to so mount the guard rail of the device that it may be adjusted to assume various positions spaced from and elevated with relation to the track 50 rails in accordance with the size of locomotive which is to run upon the track.

Another object of the invention is to so construct the supporting and adjusting means for the guard rail that by effecting 55 a single adjustment, the rail may be moved toward or away from the track rails and

simultaneously lowered or elevated in accordance with the first mentioned adjustment, thereby insuring of proper sweeping engagement of the side of the locomotive 60 against the rail in rounding the curve in the track.

Another important object of the invention is to provide a novel means for temporarily connecting together the adjacent ends of 65 adjacent sections of the guard rail structure in such a manner that the inwardly presented side of the rail against which the locomotive is to sweep, will be smooth and substantially continuous throughout its entire length, thereby reducing to a minimum 70 wear upon the rail and the locomotive.

Another important object of the invention is to provide means for connecting together, temporarily, the base members of 75 the guard rail structure sections so that the base members will present a substantially smooth and continuous upper surface to support the curved track sections.

Another object of the invention is to so construct the guard rail and supporting means therefor, that the structure will serve as a brace for the track at the portions where the curves are located and thus tend to prevent any separation of the track sections due to the thrust exerted longitudinally of the straight sections of the track by the locomotive and train rounding the curves. 85

In the accompanying drawings:

Figure 1 is a plan view of the structure 90 embodying the invention, sections of a toy railway track being associated therewith.

Figure 2 is a perspective view of one of the guard sections and a track section supported thereon. 95

Figure 3 is a bottom plan view of one of the guard sections.

Figure 4 is a vertical transverse sectional view through the connected ends of two of the guard sections. 100

Figure 5 is a side elevation of a section of the guard rail illustrating the manner in which the ends of two rail sections are connected.

Figure 6 is a horizontal sectional view on the line 6-6 of Figure 5, looking in the direction indicated by the arrows. 105

Figure 7 is a plan view of a modified form of the invention.

Figure 8 is an end elevation of one of the 110 modified sections shown in Figure 7.

Figure 9 is a vertical sectional view taken

substantially on the line 9—9 of Figure 7, looking in the direction indicated by the arrows.

Figure 10 is a perspective view similar to Figure 2, illustrating a modified form of the invention.

Figure 11 is a vertical transverse sectional view taken substantially on the line 11—11 of Figure 10.

10 Figure 12 is a vertical sectional view taken substantially on the line 12—12 of Figure 10.

The accompanying drawings illustrate a preferred and a modified form of the invention but it will be understood that various modifications may be made as will appear from the description which is to follow. Likewise, while the invention is illustrated as adapted to the track of a toy 20 electric railway, it is not restricted to such adaptation but may be employed in connection with steam driven or mechanically driven toy locomotives, and their tracks.

Referring specifically to the embodiment 25 of the invention shown in Figures 1 to 6 inclusive, the guard structure is illustrated as built up of a number of sections although the invention might be modified to the extent of manufacturing the structure integral throughout. One of the sections is clearly shown in Figure 2 of the drawings, and the said section comprises a base which is indicated in general by the numeral 1 and which is of arcuate form and comprises 30 a bottom 2 which is flat and provided at its outer periphery with an upturned inwardly curved flange 3 and at its inner periphery with a similar flange indicated by the numeral 4, the flange 4 being relatively shallow and the flange 3 being relatively deep. This relative proportioning of the flanges adapts the channeled base thus provided, to accomodate the ties 5 of a track section which is indicated in general by the numeral 45 6 and which comprises, in addition to the said ties 5, the usual three rails 7 which are mounted upon the ties and secured thereon in any suitable manner. The ties 5 are preferably formed from sheet metal 50 and are such as are usually found upon the market, and it is the custom, where the ties are a part of a curved section of track, to form the ties higher at their outer ends than at their inner ends and it will, therefore, be understood, and particularly by 55 reference to Figure 2 of the drawings, that the thicker ends of the ties are to be engaged within the concavity of the flange 3 and the thinner ends of the ties within the concavity of the flange 4, the base 1, in the assemblage of the track, being, of course, disposed flat upon the floor or other surface upon which the track is to rest, the inclination of the upper surfaces 60 of the ties toward the inner periphery of

the curve giving a desirable inclination to the locomotive as it travels around the curve. However, this is not sufficient to prevent overturning of the locomotive through centrifugal force when traveling 70 at high speed around the curve and, as previously explained, it is for this purpose and to prevent this occurrence that the present invention is designed, as will presently be made apparent. The ties 5 may be 75 seated in the channeled base in any appropriate manner, as for example, by sliding the track section into the channel of the base or forcing the ends of the ties downwardly past the upper edges of the flanges 80 3 and 4, the base being of more or less resilient metal. In any event, the base section will be made substantially of a length corresponding to the length of the ordinary curved track section in common use so that 85 other track sections supported by other bases disposed endwise to the base shown in Figure 2, may be coupled together in the usual manner. Before proceeding to a description of the rail supporting structure 90 which is associated with the base, I will first describe the illustrated means whereby two of the bases 1 may be connected together end to end. By reference to Figure 95 2 of the drawings, it will be observed that at one end of the base 1 there is secured, to the underside of the bottom 2 and to the outer sides of the flanges 3 and 4 for a portion of their height, a tongue extension 8 which is of metal of substantially the same gauge as the metal of the base, the extension having upturned flanges 9 and 10 having the same general contour as the flanges 3 and 4 respectively although of less height than said flanges 3 and 4. Referring now to Figures 2, 3 and 4 of the drawings, it will be observed that there is provided at the other end of the base 1, a pocket to receive the tongue 8 and this pocket is formed by marginally securing the flanges 11 and 12 of a plate 13, to the flanges 3 and 4 respectively of the base 1, the flanges 11 and 12 of the plate 13 being bent inwardly at their upper margins where they are united to the flanges 3 and 4, so as to provide between the said plate 13 and its flanges and the base 1 and its flanges, a space which is of a contour to a slidably and yet frictionally receive the tongue 8 and its flanges 9 and 10, the interengagement of the parts being best shown in Figure 4. At this point it will be evident that a number of sections may be connected together by fitting the said tongues 8 into the pockets of other sections and that the connection is a substantial and firm one and yet such as will permit of ready intentional separation of the connected sections.

Extending radially from the upper edge 130

of the flange 3 of the base section 1 and either secured thereto or forming an integral part therewith, are rest members indicated in general by the numeral 14, the members being, of course, of sheet metal and of substantially rectangular form and having their outer end portions bent downwardly as at 15, to provide supporting feet which are of a height greater than the height of the flange 3, so that the said supporting members will be inclined upwardly from the flange 3, as best shown in Figures 2 and 4 of the drawings, the lower ends of the supporting feet 15 occupying a horizontal plane with the underside of the bottom 2 of the base 1. For a purpose to be presently explained, each of the supporting members is formed with a longitudinally extending slot 16 and the arrangement of these slots will presently be more fully pointed out. Disposed upon the upper sides of the several supporting members 14 of the base section 1, is an arcuate base plate 17 having threaded studs 18 projecting downwardly from its underside and through the slots 16, wing nuts 19 being threaded onto the said studs 18 and being adapted to be adjusted to bind the base plate 17 against the upper sides of the said supporting members 14. The base plate 17 has fixed to it and supports, at intervals, uprights 20 which are likewise of sheet metal and which are spaced apart preferably in accordance with the spacing of the studs 18, as shown in Figure 2. The guard rail of the structure is indicated in general by the numeral 21 and the said rail comprises an arcuate strip of sheet metal which is soldered, brazed, or otherwise secured to the inwardly presented faces of the uprights 20, the curvature of the guard rail being such that the rail will be concentric to the track rails 7. At one end, and where the rail is attached to one endmost one of the uprights 20, the said rail 21 is provided with upper and lower marginal flanges 22 which are bent over in spaced parallel relationship to the outer face of the rail, and the outer faces of these flanges are united, in the manner above stated, to the inwardly presented face of the said endmost upright 20. In this manner, a socket 23 is provided at one end of the guard rail 21. The other end of the guard rail is secured, in the manner stated, to the other endmost one of the series of uprights 20 and is laterally outwardly offset, as indicated by the numeral 24, so as to provide an offset tongue 25, the end portion of which is outwardly deflected to a slight degree as indicated by the numeral 26. It will be observed that the tongue 25 projects beyond the edge of the upright to which the last mentioned end of the guard rail strip is secured and at this edge of the upright is substantially in the

same vertical plane with the corresponding end of the base plate 17. Referring now to Figures 5 and 6 of the drawings, it will be observed that when two of the guard sections are assembled end to end, not only will the tongue 25 of one of the sections be fitted into the pocket at the end of the other section but likewise, the tongue 25 just referred to will be fitted into the socket 23 at the first described end of the guard rail strip 21. The offset 24 is so proportioned that when the meeting ends of the two guard rails are fitted together, the first described end of one guard rail will abut against the offset and the inwardly arcuate faces of the assembled guard rails will, therefore, be continuous and provide a substantially unbroken smooth surface against which the side of the locomotive may sweep as the locomotive rounds the curve. By deflecting the outer end of the tongue 25 as at 26, the said end of the tongue is adapted to spring behind the inner end of the socket 23 or more specifically, behind the inner edge of the plate 21, constituting one wall of said socket and, in this manner, the parts are substantially locked in their assembled or interfitted relation.

By reference to Figure 1 of the drawings, it will be observed that the slots 16 in the supporting members 14 extend, in some instances, diagonally between the lateral edges of the supporting members and in other instances, substantially parallel to the lateral edges of the said supporting members. Thus, where a curve such is illustrated in said Figure 1, is constructed by assembling selected ones of the guard sections and track sections, the arrangement of slots will be found to be such that all of the sections comprising the base members 17, uprights 20, and rails 21, may be adjusted outwardly or inwardly with relation to the track rails of the respective track sections. It will likewise be observed that due to the inclination given the supporting members 14, outward adjustment of the guard rail will result likewise in upward adjustment of the rail to a more or less elevated position, and vice versa, inward adjustment of the rail will result in a lowering of said rail. These adjustments are, of course, effected by loosening the thumb nuts 19, shifting the base members 17, and then tightening the said nuts. The disposition of the slots furthermore, provides against relative separation of the ends of relatively adjacent guard rails 21 so that the continuity of the guard rail as a whole is not broken. In order that the guard rail sections may be adjusted with accuracy, it is desirable that a series of scale marks 27 be displayed in any suitable manner upon the upper sides of the supporting members 14 and that these marks be suitably designated so that by bringing the inner periph-

100

105

110

115

120

125

130

ery or edge of the base member 17 into registration with corresponding ones of these marks throughout its entire length, and continuing such adjustment throughout the entire series of guard rail sections, the adjustment as a whole may be effected with accuracy.

While the guard rail structure embodying the present invention is designed primarily for use on curves, it may be likewise well adapted for employment in connection with straight track sections and particularly the straight track sections which lead to or from the curved track sections, as illustrated for example, in Figure 1 of the drawings, in which figure the numeral 28 indicates one of such straight track sections and the guard structure associated therewith, the structure being identical with that previously described except that the guard rail is straight and, therefore, tangential to the curved track section with which the straight track section 28 is assembled end to end. In such a case it may be found desirable to extend the guard rail the entire length of the straight track section or it may extend only a portion of the length of such section, the object in view being to steady the locomotive and train as it leaves the curved track section and guide it toward a straight section and, on the other hand, to guide the side of the locomotive into sweeping engagement with the rail extending beside the curved track section, when the locomotive approaches said last named section.

In the above described and illustrated embodiment of the invention, the guard structure is initially separate and distinct from the track structure and the sections of the track structure are to be assembled with the sections of the guard structure but if found expedient, the two structures may be combined as one by mounting the rails of the track structure directly upon the bases of the guard structure sections and with this end in view, the rails may be supported in an elevated position by any suitable means so as to bring them to the same elevation as the tie supported rails of the ordinary straight track sections, or the bases of the guard rail structure sections might be formed solid or of a thickness to accomplish this result. These, however, are mere adaptations of the general idea involved and various changes may be made without departing from the spirit of the invention.

Figures 7, 8 and 9 of the drawings illustrate a slight modification of the invention, the structure being somewhat simplified and of a unitary nature. In these figures, the track rails are indicated by the numeral 29 and are mounted upon ties 30 which are of sheet metal and are formed from blank suitably folded or stamped to adapt the rails to be suitably supported thereby,

and certain of the ties are provided at their outer ends with integral extensions 31 which are deflected upwardly to provide standards 32 corresponding in purpose to the standards 20 of the previously described form of the invention. The guard rail in these figures is indicated by the numeral 33 and is secured to the inner surfaces of the standards 32 in any appropriate manner. The ends of the guard rail sections are provided with extensions 34 integral therewith and extending downwardly and outwardly at an angle of inclination and cut obliquely at their lower ends as at 35 to rest upon the floor or other surface upon which the track is laid. Likewise, in this embodiment of the invention, the adjacent or meeting ends of two track sections are connected by means of a key plate which is indicated by the numeral 36 and which comprises a sheet metal plate having its opposite marginal portions turned upwardly and inwardly to provide locking flanges 37, the flanges being so spaced as to adapt the said plate to be slidably fitted to two adjacent ones of the ties 30 with the relatively remote flanges 38 of the base portions of the ties beneath the flanges 37 of the plate 36. In this manner the track sections may be firmly connected together and, at the same time, may be readily separated by slidably withdrawing the key plate from engagement with the ties.

Referring now to the form of the invention illustrated in Figures 10, 11 and 12 of the drawings, it will be observed that the structure is, in general, substantially the same as in the previously described form. In the said figures of the drawings, the numeral 40 indicates in general the base of the structure which, as in the previously described form, is made of sheet metal as well as substantially all of the other parts of the modification. Said base includes a bottom 41 and upstanding flanges 42 and 43, the flange 42 being of less height than the flange 43 so that the thinner end of a rail supporting tie 44 may be received within the through-like base in juxtaposition to the flange 42, and the thicker end of said tie may be received within the structure in juxtaposition to the flange 43 which is of greater height than the flange 42. The ties 44 support the usual rails 45 as previously described, and the usual separable connection is provided between the meeting ends of the rails. United in any suitable manner to the upper edge of the flange 42 of the base is one marginal portion of a strip 46, this portion of the strip projecting inwardly beyond the plane of the flange 42 and being slightly turned downwardly as indicated by the numeral 47, so as to engage over the adjacent ends

of the said ties 44, the other marginal portion of the strip 46 being turned downwardly to assume a substantially vertical position as indicated by the numeral 48, and to adapt its lower edge to rest upon the floor surface upon which the entire track structure is disposed. A similar strip 49 is united at its under side and at one marginal portion to the upper edge of the flange 43, in any desired manner, and said marginal portion of the strip is turned slightly downwardly as indicated by the numeral 50, so as to engage over the thicker ends of the ties 44. The outer marginal portion of the strip 49 is turned downwardly substantially perpendicularly, as indicated by the numeral 51, and is preferably provided with an outstanding horizontal base flange 52 designed to rest upon the surface upon which the track structure is arranged. As the structure just described is employed in curved track sections, it will be understood that identically the same arrangement will be present in straight track sections except that the flanges 42 and 43 will be of the same height or of nearly the same height, the straight track sections referred to being those which are connected at the ends of the curved track sections and which would, therefore, correspond, for example, to such sections as those indicated by the numeral 28 and shown in Figure 1 of the drawings. At this point it will be observed that in this form of the invention, the strip members 46 and 49 lie or extend at opposite sides of the base 40 which supports the rail structure comprising the ties 44 and rails 45, and constitutes substantially the equivalent of the members 14, except that the modified structure presents this advantage, namely, that the upper surfaces of the strip members 46 and 49 may be painted, surfaced, or, in any other manner found suitable, made to resemble sod, thereby adding to the attractiveness of the structure. Likewise, a more rigid and substantial structure is produced.

The sections embodying the modified features illustrated in the said Figures 10 to 12 inclusive, may be connected together by the means illustrated most clearly in Figures 10 and 12 of the drawings, and comprising tongue members 53 and 54 projecting beyond the ends of the strip members 46 and 49 of each section, at one end of the section, and secured in any suitable manner to the under sides of the said strip members and each provided with a deflected portion or bend 55 which serves a purpose which will now be explained. Secured to the under sides of the strip members 46 and 49 at their other ends, are transverse keeper plates 56 and 57 respectively, the ends of the plates being secured to the said strip members and the intermediate por-

tion of the plates being spaced from the under sides of the said members so as to accommodate the tongues 53 and 54 respectively, the offsets or bends 55 in the tongues being designed to engage behind the inner 70 edges of the respective plates 56 and 57. In this manner, the meeting ends of adjacent sections may be securely connected together and yet they may be readily separated when occasion requires.

In some makes of toy electric locomotives, the locomotive is provided at one or both sides with a trip arm by means of which the locomotive may be reversed. The distance to which these arms project beyond the chassis of the locomotives of different types differs to some extent, and in order to insure against accidental reversal of the locomotive while traveling and through contact of the trip arm with some portion of the 85 guard rail structure, the present invention, so far as regards the modification now being described, contemplates mounting the guard rail, which is indicated by the numeral 58, upon outstanding sheet metal 90 bracket members 59 which are suitably fixed to upstanding posts 60 mounted, in a manner which will now be explained, upon the upper side of the outer strip member 49. The posts 60 are preferably of cylindrical 95 form and made from sheet metal and may be coated or otherwise acted upon to resemble fence posts, and each post at its lower end is provided with a base flange 61 and with a threaded stud 62 projecting 100 downwardly axially of the post and having thereon a wing nut 63. The studs 62 of the posts fit through slots 64 which are formed in the said strip member 49 and which are suitably disposed at the proper angle as in the instance of the slot 16 in the first described form of the invention, it being understood that the guard rail structure is, in this manner, mounted for 105 adjustment toward and from the track structure and held in positions of adjustment by tightening the said wing nuts 63.

From the foregoing description of this form of the invention, it will be evident that various equivalent forms of the bracket members 59 may be employed in the previously described forms to obtain the said beneficial results.

Having thus described the invention, what I claim is:

1. The combination with a toy railway track, of a guard rail extending in elevated position beside and in spaced relation to the track in position for sweeping engagement by the body of a car traveling upon the track.

2. The combination with a toy railway track, of a guard rail, and means supporting the guard rail in elevated position beside and in spaced relation to the track in

position for sweeping engagement by the body of a car traveling upon the track, the said rail being adjustable toward and from the track.

5. The combination with a toy railway track, of a guard rail having a smooth, unobstructed surface, the said rail extending in elevated position beside and in spaced relation to the track in position for sweeping engagement by the body of a car traveling upon the track.

4. The combination with a toy railway track, of a support fixed with relation to the track, a member mounted upon the support 15 for adjustment toward and from the said track, and a guard rail supported by the said member in position sufficiently elevated above the track for sweeping engagement by the body of a car traveling upon the 20 track.

5. The combination with a toy railway track, of a support fixed with relation to the track, a member adjustably mounted upon the support and in its adjustment being 25 movable toward and away from the said track, and a guard rail supported by the said member and having a smooth unobstructed face presented toward the track, the said guard rail being supported above 30 the plane of the track and in position to be engaged by the body of a car traveling upon the track.

6. The combination with a toy railway track, of a support extending laterally outwardly beyond the track, and a guard rail structure supported upon the said support 35 for adjustment toward and from the track.

7. The combination with a toy railway track, of a support extending laterally outwardly and inclined upwardly from the track, and a guard rail adjustably mounted 40 upon the said support for movement toward and away from the said track.

8. The combination with a toy railway track the line of extent of which is a curve, 45 of supports extending radially outwardly from the track and provided with slots, a base member disposed upon the supports, means associated with the base member and engaging through the slots for securing the base member in positions of adjustment upon the support more or less remote from the said track, and a guard rail mounted 50 upon the supporting member, the direction of extent of the slots being such as to maintain concentric relation between the track and the guard rail in all positions of adjustment of the guard rail.

9. The combination with a toy railway track the line of extent of which is a curve, 60 of supports extending radially outwardly from the track and provided with slots, a base member disposed upon the supports, means associated with the base member and engaging through the slots for securing the 65

base member in positions of adjustment upon the support more or less remote from the said track, and a guard rail mounted upon the supporting member, the direction of extent of the slots being such as to maintain concentric relation between the track and the guard rail in all positions of adjustment of the guard rail, the said supports being provided with indicating scale marks for the registration therewith of a portion of the base member.

10. The combination with a toy railway track comprising a plurality of track sections the line of extent of which is a curve, of supports extending radially outwardly from the track sections, a base member disposed movably upon the supports of each track section, a guard rail mounted upon each base member, the said supports having slots, means associated with the base member of each rail section engaging through the slots of the respective supports for securing the base member in positions of adjustment more or less removed from the track section, the arrangement of the slots being such as to provide for maintenance of the guard rail in concentric relation to the track sections in all positions of adjustment of the base member, and means upon the said rails providing for connection of the meeting ends of relatively adjacent rails of the several track sections.

11. A guard rail for toy railway tracks comprising supporting means, a guard rail mounted thereon, the guard rail being provided at one end with a socket, and a tongue extending from the other end of the guard rail and having a deflected end whereby a plurality of the guard rails may be assembled end to end with the tongue of one rail engaging in the socket in the meeting end of the next adjacent rail.

12. A guard rail for toy railway tracks comprising supporting means, a guard rail mounted thereon, the guard rail being provided at one end with a socket, and a tongue extending from the other end of the guard rail and having a deflected end whereby a plurality of the guard rails may be assembled end to end with the tongue of one rail engaging in the socket in the meeting end of the next adjacent rail, the said socket being open at both ends, whereby the said deflected end of the tongue may be engaged behind the end edge of one wall of the socket.

13. A guard rail for toy railway tracks comprising supporting means, uprights thereon, a guard rail of sheet metal supported by the uprights and having a smooth surface against which the side of a car may have sweeping engagement, the rail at one end being provided with overturned extensions at its upper and lower edges constituting one wall of a pocket, the end portion of the rail which carries the said extensions

- constituting the other wall of the pocket, the other end of the rail being offset in a direction away from the said base of the rail and provided with a tongue extending 5 longitudinally from the said end of the rail and having a deflected end, the said rail being adapted to be thereby assembled with a counterpart rail with the tongue of one rail fitting frictionally and removably in 10 the socket of the other rail and with the deflected end of the tongue engaging behind the inner end edges of the overturned portions of the second mentioned rail to constitute a friction lock, the offset being of a width substantially equal to the thickness of the rail whereby a flush and smooth joint is provided between the meeting ends of the rails and whereby the continuity of said 15 faces of the rails is not interrupted.
14. A guard rail structure for toy railway tracks comprising a base member, means thereon for supporting the usual track comprising the usual ties and rails, a support extending laterally outwardly from the said base, and a guard rail adjustably mounted upon the said support and being movable, in its adjustment, toward and from the adjacent side of the base. 20
15. A guard rail structure for toy railway tracks comprising a base, means upon the base for engaging the ends of the ties of the ordinary track comprising said ties and rails supported thereon, a support extending laterally outwardly from one side of the 25 said base, a base member movably supported by the said support, means for securing the base member in positions of adjustment upon the support, uprights upon the base member, and a guard rail supported by the uprights 30 and having substantially the same line of extent as the rails of the track.
16. A guard rail structure for toy railway tracks comprising a base for supporting the usual track comprising the usual tie members and rails supported thereby, the base being provided along its opposite sides with upwardly and inwardly turned flanges to engage over the ends of the said tie members of the track, a supporting member extending outwardly from one side of the base, 35 a base member adjustably mounted upon the
- supporting member, means for holding the base member in positions of adjustment, and a guard rail supported by the said base member and having a smooth side presented 55 in the general direction of the said base.
17. A guard rail structure for toy railway tracks comprising a base for supporting a section of ordinary track comprising the usual tie members and rails supported thereby, means for retaining the ties in place upon the said base, a guard rail supported by the base and extending beside the same on the same general line of extent thereof, the base being provided at one end with a 60 pocket and at its other end with a tongue frictionally engageable in the pocket of a counterpart structure whereby a plurality of the structures may be connected together 65 end to end. 70
18. A guard rail structure for toy railway tracks comprising a base, means thereon for retaining in place a section of track of the usual construction embodying tie members and rails, supporting members extending 75 outwardly from one side of the base and inclined upwardly toward their outer ends, feet extending downwardly from the outer ends of said supporting members whereby to sustain the same, a supporting base adjustably mounted upon the supporting members and in its adjustment movable toward and away from the said base, and by reason of the inclination of the supporting members, having a vertical as well as lateral adjustment, and a guard rail supported upon the supporting base and having a smooth side presented 80 in the general direction of the first mentioned base. 85
19. A toy railway track comprising a 90 straight stretch and a curved stretch, and a guard rail extending continuously outwardly of and in spaced relation to the curved stretch and for a portion of the length of the straight stretch and elevated 95 above the track and having a smooth surface for engagement by the side of the body of a car traveling upon the track.

In testimony whereof I affix my signature.

WALTER M. FISCHBACH. [L.S.]
